UNITED STATES PATENT OFFICE.

HERBERT C. WIRT, OF SCHENECTADY, NEW YORK, ASSIGNOR TO THE
GENERAL ELECTRIC COMPANY, OF NEW YORK.

DESIGN FOR A LIGHTNING-ARRESTER.

SPECIFICATION forming part of Design No. 29,371, dated September 20, 1898.

Application filed August 29, 1898. Serial No. 689,808. Term of patent 14 years.

To all whom it may concern:

Be it known that I, HERBERT C. WIRT, a citizen of the United States, residing at Schenectady, in the county of Schenectady, State 5 of New York, have invented and produced a new and original Design for a Lightning-Arrester, (Case No. 932,) of which the following is a specification.

The leading feature of the design consists 10 in the peculiar arrangement and configuration of the several parts, as shown.

Referring by letter to the drawing, A represents the insulating base or support, which is chamfered at B. Holes C are provided for 15 the reception of screws or other devices for securing the support in place. Mounted on the front of the support is a cylindrical body D, of resistance material, which is employed to limit the flow of dynamo-current after a 20 lightning discharge takes place. This resistance is secured in place on the front of the

support by means of clips E and F, located, respectively, at the ends of the resistance. The clip F is extended upwardly to form a line-terminal F', while the clip E is extended 25 downwardly at E' to form a support for the large metal cylinder G. Situated below the cylinder G and separated therefrom by an air-space is a second cylinder H, which is similar to the first. This cylinder is mounted 30 on a suitable support I, which also forms a binding-post.

What I claim is—

The design for a lightning-arrester, substantially as shown and described. 35

In witness whereof I have hereunto set my hand this 24th day of August, 1898.

HERBERT C. WIRT.
